UNITED STATES PATENT OFFICE.

ANNIE P. DALZELL, OF FINDLAY, OHIO, ADMINISTRATRIX OF JAMES DALZELL, DECEASED.

DESIGN FOR A STALACTITE FOR ELECTRIC LAMPS.

SPECIFICATION forming part of Design No. 22,712, dated August 15, 1893.

Application filed July 13, 1893. Serial No. 480,441. Term of patent 7 years.

To all whom it may concern:

Be it known that JAMES DALZELL, deceased, formerly of Findlay, in the county of Hancock, State of Ohio, did invent a new and original Design for Stalactites for Electric Lamps, of which the following is a full, clear, and exact description, reference being had to the accompanying drawing, forming part of this specification, which represents a side elevation of a stalactite showing the design.

The leading feature of the design consists in a stalactite or shade having a series of diamond-shaped projections upon its surface, these projections gradually diminishing in size toward the bottom.

In the drawing, 2 indicates the stalactite, and 3 the diamond-shaped projections upon its outer surface, these projections being made gradually smaller toward the bottom of the shade.

What is claimed is—

The design for stalactites for electric lamps, substantially as herein shown and described.

In testimony whereof I, the said ANNIE P. DALZELL, administratrix of JAMES DALZELL, deceased, have hereunto set my hand.

ANNIE P. DALZELL,
Administratrix of James Dalzell, deceased.
